FIG-1

FIG-2

FIG-3

FIG. 1 is a top plan view of a helicopter showing our new design;

FIG. 2 is a side elevation thereof;

FIG. 3 is a front elevation thereof;

FIG. 4 is a rear perspective view of the helicopter; and

FIG. 5 is a front perspective view taken from the side opposite that shown in FIG. 4.

The ends of the main rotor blades in the several views have been broken away for convenience of illustration only.

The dominant features of the design reside in the portions shown in full line.

We claim:

The ornamental design for a helicopter, as shown and described.
